UNITED STATES PATENT OFFICE

JULIUS DINHOFER, OF NEW YORK, N. Y.

DESIGN FOR PRECIOUS, SEMIPRECIOUS, OR SYNTHETIC CUT STONE

Application filed November 23, 1929. Serial No. 33,530. Term of patent 7 years.

To all whom it may concern:

Be it known that I, JULIUS DINHOFER, a citizen of the United States, and a resident of the city, county, and State of New York, have invented a new, original, and ornamental Design for Precious, Semiprecious or Synthetic Cut Stone, of which the following is a specification, reference being had to the accompanying drawing, forming a part hereof, in which—

Figure 1 is a plan view of a cut stone, showing my new design;

Figure 2 is a side elevation of the same, and

Figure 3 is a view of the under face of the same.

I claim:

The ornamental design for precious, semiprecious or synthetic cut stone, as shown.

JULIUS DINHOFER.
